[57] **CLAIM**

The ornamental design for a flexible covering for partitions or the like, as shown and described.

DESCRIPTION

FIG. 1 is a front elevational view of a flexible covering for partitions or the like showing my new design, the rear being identical;

FIG. 2 is an enlarged perspective view thereof, shown applied to the convex surface of a partition;

FIG. 3 is a side elevational view taken from the right of FIG. 2;

FIG. 4 is an enlarged perspective view thereof, shown applied to the flat surface of a partition;

FIG. 5 is an enlarged perspective view thereof, shown applied to the concave surface of a partition.

The broken lines in FIGS. 2, 3, 4, and 5 are for illustrative purposes only, and disclose environmental applications of the design.
